UNITED STATES PATENT OFFICE.

PAUL CRICCHIO, OF NEW YORK, N. Y., ASSIGNOR TO SUN RISE LAMP MFG. CO., INC., A CORPORATION OF NEW YORK.

DESIGN FOR A CANDLESTICK OR ANALOGOUS ARTICLE.

Application filed May 16, 1927. Serial No. 22,000. Term of patent 3½ years.

To all whom it may concern:

Be it known that I, PAUL CRICCHIO, a citizen of the United States, and a resident of New York, county of Bronx, and State of New York, have invented a new, original, and ornamental Design for a Candlestick or Analogous Article, of which the following is a specification, reference being had to the drawing forming a part thereof.

In the drawing:

I claim:

The ornamental design for a candlestick or analogous article substantially as shown.

PAUL CRICCHIO.
